A. MAYER,
IGNITION CUT-OUT,
APPLICATION FILED DEC. 10, 1921.

1,438,388.

Patented Dec. 12, 1922.

Inventor
Arthur Mayer
By his Attorney
Maurice Block

UNITED STATES PATENT OFFICE.

ARTHUR MAYER, OF NEW YORK, N. Y.

IGNITION CUT-OUT.

Application filed December 10, 1921. Serial No. 521,302.

To all whom it may concern:

Be it known that I, ARTHUR MAYER, a resident of New York city, county and State of New York, and a citizen of the United States of America, have invented certain new and useful Improvements in Ignition Cut-Outs, of which the following is a specification.

This invention relates to improvements in locking means for the ignition of internal combustion motors, particularly of the class used to operate motor vehicles. To carry my invention into practice, I break the ignition circuit at the distributor or device to electrically connect the ignition plugs at the proper time relative to the operation of the pistons. To accomplish this result, I employ a special form of distributor arranged so that the circuit for the plugs can be broken and maintained broken until the device is reset, special means being provided to lock the device in either off or on position.

I will now proceed to describe my invention in detail, the novel features of which I will point out in the appended claims, reference being had to the accompanying drawing wherein:—

Fig. 1 is a sectional view, partly in elevation, of an ignition distributor embodying my improvement;

Fig. 2 is a top plan view thereof on a reduced scale;

Fig. 3 is a sectional plan view, the section being taken on a line 3—3 in Fig. 1;

Fig. 4 is a fragmentary edge view of a portion of the movable disk, illustrating the locking pin and also a portion of the distributor casing; and

Fig. 5 is an edge view of a distributor embodying my improvement.

In the drawing I have illustrated my invention as incorporated in a well known type of distributor consisting of a carrier made up of a casing 6 which carries a timer or rotating arm 7 carrying a contact 8 in circuit with a metal strip 9 having in contact therewith a pin 10 which in turn has connected thereto a high tension lead, indicated by 11, the low tension circuit and breaker being omitted. The pin 10 is carried by a removable cap or cover 12 which also carries conductors 13, 14, 15 and 16, each of which is connected to its respective spark plug (not shown), the distributor herein illustrated being for a four

cylinder motor. The cap 12 is removably connected to the casing 6 by means of a non-yieldable clip 16^a and a yieldable latch 17. The casing 12 is provided with an annular flange 18 having cut away portions 18^a and 19 and a recess 20. When the cap 12 is in position upon the casing 6, the clip 16^a will overlap the flange 18, while latch 17 will engage recess 20. To remove the cap, latch 17 will be pulled out of recess 20 and the cap revolved to the right to cause the cut away portions 18^a and 19 to align with the clip 16 and latch 17, respectively, after which the cap can be removed. The cap cannot be removed by merely pulling the latch 17 out of the recess 20; clip 16^a must be caused to align with the cut away portion 18^a.

To carry my invention into practice, I provide a rotatable disk 21 having teeth 22 in mesh with a worm gear 23, (in this instance) carried by the casing 12. The disk 21 is rotatably held in place, within cap 12, by a ring 24 screwed into the cap. The disk 21 carries conductors 25, 26, 27 and 28, each being yieldably mounted in a casing 29 and forced outwardly or upwardly by a spring 31 to cause same to contact with the conductors 13, 14, 15 and 16. During the rotation of arm 7, the contact 8 will impinge upon the conductors 25, 26, 27 and 28; hence, the circuit for each plug will be completed for the reason that said contacts will rest against conductors 13, 14, 15 and 16. To break the ignition circuit, the disk 21 will be rotated (in this instance) in the direction of the arrow 31 until the conductors 25, 26, 27 and 28 are moved away from their respective conductors 13, 14, 15 and 16 far enough to prevent a spark from jumping from the contacts 13 to 16 to the contacts 25 to 28 when disk 21 is in off position, as indicated by dotted lines in Fig. 3.

To rotate disk 21, worm 23 will be rotated, and for this purpose I mount worm 23 upon a shaft 32, one end 33 of which is journaled in cap 12, the other end 34 being connected to the cylinder 35 of a pin-cylinder lock mechanism, the casing 36 for which is secured in position in cover 12 by a pin 37. The outer end of the cylinder 34 of the lock carries a hand-wheel 38 by means of which the cylinder 35, shaft 32 and worm 23 are rotated, when cylinder 35 is unlocked. The cylinder 35 will be

locked to its casing by pins (not shown) in the usual manner, said cylinder 35 being released from casing 36 by a key inserted into the key-hole 39. The disk 21 will be 5 locked in both the on and off position. To move the disk 21 from on to off, or vice versa, the cylinder 35 will be released from its casing 36 by the key provided for the purpose. When disk 21 is moved to off 10 position, the cover 12 will be locked against rotation; hence, cannot be removed from the distributor casing 6. To accomplish this, I provide the ring 24 with a pin 40 operated by a cam slot 41 in the disk 21 15 (see Fig. 4), arranged to engage a recess 42 in casing 6. When disk 24 is rotated, the pin 40 will be moved into the recess 42; hence, the cap or casing 12 cannot be rotated even though latch 17 is moved out of 20 recess 20 (see dotted lines Fig. 4). When disk 21 is moved to off position, the casing or cap 12 will be locked so that it cannot be moved. When disk 21 is in off position, the worm 23 will be locked; hence, disk 21 can 25 not be moved to on position even though the cap or casing is removed after cutting the flange 18^a away so that clip 16^a can be slipped off flange 18^a. When disk 21 is moved to off position, the circuit for the plugs will be 30 broken; hence, the motor cannot be operated.

A further feature of the improvement resides in providing cap 12 with a supplemental contact 43 (Fig. 2) which by means 35 of a wire 44 can be connected to a gear-shift-lever emergency brake, clutch pedal, brake pedal or starter switch. The contact 43 will be positioned so that when the disk 21 is in off position, a conductor carried by disk 21 40 will contact therewith, in this instance, contact 27. Should an attempt be made to start the motor, the person doing same would receive a shock as soon as contact 8 came into contact with contact 43.

45 As conductors 13 to 16 are larger in diameter than conductors 25 to 28, it is possible to alter the firing point of a motor by shifting disk 21 to the right or left across the face of conductors 13 to 16 whereby the contacting of contact 8 with the casings for the conductors 25 to 28 will either be advanced 50 or retarded. By shifting disk 21 to the right or left, the sparking point of a motor can be advanced or retarded within the limits of 55 the face of the conductors 13 to 16.

What I claim and desire to secure by Letters Patent is:—

1. In a distributor for ignition systems, a casing, a cap carried thereby normally removable therefrom, conductors for high tension current carried thereby, a rotary timer within the casing arranged to contact with said conductors, a circuit breaker within the distributor arranged to break the circuit between said timer and said conductors, means

operable exteriorly of the distributor to operate the circuit breaker, means to lock the cap against removal when the circuit breaker is moved to off position, and means to lock the circuit breaker against movement. 70

2. In a distributor for ignition systems, a casing, a cap carried thereby normally removable therefrom, conductors for high tension current carried thereby, a rotary timer within the casing arranged to contact with said conductors, a circuit breaker within the distributor arranged to break the circuit between said timer and said conductors, means operable exteriorly of the distributor to operate the circuit breaker, means to lock the 75 cap against removal when the circuit breaker is moved to off position, means to lock the circuit breaker against movement, and a supplemental conductor for high tension current carried by the cap arranged to be connected in circuit with the timer, when the circuit breaker is moved to off position.

3. In a distributor for ignition systems, a casing, a cap carried thereby normally removable therefrom, a rotatable circuit breaker within the cap, conductors for high tension current carried by the cap, a rotatable disk within the cap, conductors carried by the disk normally in contact with the conductors carried by the cap, a rotary timer 90 within the distributor arranged to contact with the conductors carried by the disk, teeth carried by the circuit breaker, a gear carried by the casing to rotate the circuit breaker, means to operate the gear exteriorly 100 of the distributor to move the circuit breaker to off position, means operable by the circuit breaker to lock the cap against removal when the circuit breaker is moved to off position, and means to lock the circuit breaker 105 operating gear against movement.

4. In a distributor for ignition systems, a casing, a cap carried thereby normally removable therefrom, a rotatable circuit breaker within the cap, conductors for high tension current carried by the cap, a rotatable disk within the cap, conductors carried by the disk normally in contact with the conductors carried by the cap, a rotary timer 110 within the distributor arranged to contact with the conductors carried by the disk, teeth carried by the circuit breaker, a gear carried by the casing to rotate the circuit breaker, means to operate the gear exteriorly 115 of the distributor to move the circuit breaker to off position, means operable by the circuit breaker to lock the cap against removal when the circuit breaker is moved to off position, means to lock the circuit breaker operating gear against movement, and a supplemental conductor carried by the cap arranged to contact with one of the conductors carried by the circuit breaker, when the circuit breaker is moved to off position. 120

5. In combination with a distributor for 125

130

ignition systems having a removable cap, a circuit breaker within the distributor, and operable exteriorly thereof, to break the ignition circuit controlled by the distributor, and means associated with the circuit breaker to lock the cap against removal when the ignition circuit is broken. 5

ductors, a circuit breaker within the distributor, means to break the high tension circuit controlled by the distributor at will, and means to ground the high tension circuit when the circuit, through the conductors of the distributor, is broken. 10

6. In combination with a distributor for ignition systems having high tension con-
